SUSIE J. MERCER, Primary Examiner

FIG. 1 is a perspective view of a lighter-pen combination with magnetized telescopic tip, showing the embodiment of my new design;

FIG. 2 is a top plan view thereof;

FIG. 3 is a side elevational view thereof showing the opposite side of the perspective;

FIG. 4 is a rear elevational view thereof;

FIG. 5 is a bottom plan view thereof; and

FIG. 6 is a partially broken, exploded perspective view showing the telescoping effect and the lighting member of the lighter.

The Lighter is broken away in FIG. 6 for convenience of illustration.
